UNITED STATES PATENT OFFICE.

PETER J. NAGLE, OF ROCHESTER, NEW YORK.

TOY BANK.

Specification of Letters Patent. Patented Aug. 31, 1915.

1,151,606.

Application filed April 16, 1915. Serial No. 21,780.

To all whom it may concern:

Be it known that I, PETER J. NAGLE, of Rochester, in the county of Monroe and State of New York, have invented a new and useful Toy Bank, fully set forth in the following specification and shown in the accompanying drawings.

The present invention relates to toy banks and an object of the same is to provide a simple and inexpensive construction which may be made from paper board and have provision for preventing the discharge of the coins introduced therein.

To this and other ends, the invention consists in certain parts and combinations of parts all of which will be hereinafter described, the novel features being pointed out in the appended claims.

In the drawings: Figure 1 is a perspective view of a bank constructed in accordance with the present invention; Fig. 2 is a vertical section through the bank; Fig. 3 is a perspective view of the end closure provided with the coin slot closing means; and Fig. 4 is a section on the line *a—a*, Fig. 2 with the covering of the bank removed.

Referring more particularly to the drawing, 1 indicates a body member which is preferably rectangular in cross section and 30 is open at opposite ends. One end of this member may be closed by a closure 2 provided with surrounding flanges 3 fitting within the open end of the body 1. The other end of the body may be closed by a closure 4 having two extensions 5 at opposite 35 sides thereof extending into the body member and co-operating with the inner face of the closure 2, thus holding the two closures 2 and 4 in properly spaced relation, the two extensions 5 preferably being cut away 40 at 6 for the purpose of receiving the flanges 3. Either or both of these extensions 5 may be provided with tongues formed in one piece with the extensions 5 and connected 45 to the latter by scores 8. These tongues 7 are less in width than the extensions 5 and are free to move downwardly when a coin is introduced through the coin slot 9 in the closure 2. The spring or natural tend-

ency of the stock of the tongue 7 is to hold 50 either one of them in a position to close the slot while the other lies beneath the same and exerts an upward pressure on it.

The bank as a whole may be covered with 55 paper ornamented or printed in any suitable manner. Preferably two end pieces 10 are employed each of which overlies one of the end closures, and a band 11 surrounds the body member and overlaps the edges of 60 the end pieces 10.

A toy bank constructed in accordance 65 with this invention is inexpensive to manufacture. It may be formed entirely of paper board and is reinforced in such a manner as to be very durable. The end closures 70 are held properly spaced from each other without any fastening devices other than the wrapping pieces which cover them and the body member. The coin slot is closed by portions which are in one piece with an end 70 closure so that a separate operation for fastening the coin slot closures to the box is unnecessary.

What I claim as my invention and desire 75 to secure by Letters Patent is:

1. A toy bank comprising an open ended body member and closures for the opposite ends of said member, one of said closures being provided with a coin slot and the other of said closures having a portion at one 80 side thereof extending into said body member in close proximity to the inner face of one of the side walls and carrying a movable laterally extending flap on the inside of the body member to close the coin slot to prevent the 85 discharge of the coins.

2. A toy bank comprising a body member, a closure for one end of said member having a coin slot, and a closure for the opposite end of the body having lateral 90 extensions at opposite sides thereof lying entirely within the body member in close proximity to opposite side walls of the latter, with the closure having the coin slot to support the last named closure, one at least of 95 said extensions being provided with a tongue for closing said coin slot.

3. A toy bank comprising an open-ended

body member, two closures fitting into the open ends of said body member, one being provided with a coin slot, and the other being provided with two extensions on opposite sides coöperating with the inner face of the other closure, said extensions having tongues at their ends in one piece with the

extensions and connected to the latter by scores, the tongues normally closing the coin slot, and a covering for the bank holding the closures to the open-ended body member. 10

PETER J. NAGLE.
